CLAIM

The ornamental design for a processing system, as shown and described.

DESCRIPTION

FIG. 1 is a perspective view of a first embodiment of a processing system showing our new design;

FIG. 2 is a front elevational view of the embodiment of FIG. 1;

FIG. 3 is a right side elevational view of the embodiment of FIG. 1;

FIG. 4 is a rear elevational view of the embodiment of FIG. 1;

FIG. 5 is a left side elevational view of the embodiment of FIG. 1;

FIG. 6 is a top plan view of the embodiment of FIG. 1;

FIG. 7 is a front elevational view of a second embodiment of a processing system showing our new design;

FIG. 8 is a right side elevational view of the embodiment of FIG. 7;

FIG. 9 is a rear elevational view of the embodiment of FIG. 7;

FIG. 10 is a top plan view of the embodiment of FIG. 7.

FIG. 11 is a front elevational view of a third embodiment of a processing system showing our new design;

FIG. 12 is a rear elevational view of the embodiment of FIG. 11;

FIG. 13 is a left side elevational view of the embodiment of FIG. 11; and

FIG. 14 is a top plan view of the embodiment of FIG. 11.
